UNITED STATES PATENT OFFICE.

WILLIAM L. REID, OF LIMA, OHIO.

LOCOMOTIVE STEAM PIPES.

Application filed June 22, 1923. Serial No. 647,138.

This invention relates to steam pipes for locomotives and one of the primary objects of the invention is to provide a construction in which there is flexibility in the steam pipes sufficient to overcome the following difficulties.

It has been found that there is a measurable difference in expansion between the steam pipes in the smoke box and the smoke box itself. The smoke box is, of course, subject to the heat of the smoke box gases, but it is also exteriorly cooled by the air, and is cooler than the steam pipes which are partly encased in the smoke box and surrounded by smoke box gases for a portion of their length. The steam pipes expand more than the smoke box and, therefore, there is a very serious strain and upward thrust at the connection between the steam pipes and the superheater header or the throttle, as the case may be. In standard practice, the steam pipe lines leading to each cylinder from the superheater header or from the throttle are made in single castings which are heavy and unyielding and which, therefore, transmit these expansion strains directly to the connection to the header or to the throttle.

In operation, it is not at all infrequent that the expansion of the steam pipes wrenches the header loose from its connection to the flue sheet or that the throttle is pushed upwardly in the smoke box and the smoke box shell or throttle case distorted, necessitating resort to frequent repairs.

My invention is designed to overcome these difficulties.

The foregoing, together with such other objects as may hereinafter appear, or are incident to my invention, I obtain by means of a construction which I have illustrated in preferred form in the accompanying drawings, wherein:

Fig. 1 is a diagrammatic side elevation of a portion of a locomotive boiler and smoke box, partially broken out to illustrate the application of my improvements;

Fig. 2 is a section taken on the line 2—2 of Fig. 1, both Fig. 1 and Fig. 2 showing an arrangement in which the steam pipes are connected to the superheater header.

Fig. 3 is a partial side elevation and section, corresponding to Fig. 1, but illustrating the application of my improvements to an arrangement in which the steam pipes are connected to a throttle in advance of the superheater header; and

Fig. 4 is a section taken on the line 4—4 of Fig. 3.

Referring now to Figs. 1 and 2, the reference numeral 7 indicates the forward end 60 of the boiler of the locomotive, having the usual flue sheet 8 in advance of which is the smoke box 9. A dry pipe 10 leads from the dome 11 to the flue sheet 8 where connection is made to the inlet side of the superheater 65 header 12 by means of the usual joint 13, the superheater header being bolted to the flue sheet in the usual manner. The steam pipes, indicated as a whole by the reference letter A, lead from the outlet side of the super- 70 heater header 12 to the valve chests 14, respectively.

Each steam pipe is connected to the superheater header and to the respective valve chest by means of the joints 15 and 16. 75 These joints are of standard flanged type, customarily employed in steam pipes and have a certain amount of aligning flexibility, for which purpose the male and female members are usually made with their interengaging 80 portions spherical.

It will be noted, however, that each steam pipe, instead of being made as a single casting, as heretofore, is composed of two sections 17 and 18, which sections are connected 85 together by a joint 19 of the same character as the joints 15 and 16. These joints are angularly disposed with reference to one another, as will be clear on inspection of the drawings, and the arrangement is such as 90 to provide a measure of flexibility in the steam pipes sufficient to take care of the greater expansion of the steam pipes, without imposing the strains or thrust on the coupling between the superheater header and 95 the flue sheet heretofore described.

In the arrangement of Figs. 3 and 4, the dry pipe 10 is located exteriorly of the boiler, and the steam pipes, instead of being coupled to the superheater header 12, are connected 100 to the throttle casing 20, which is located in advance of the stack 21 and is connected to the superheater header by the member 22, coupled to the superheater header by a joint 105 23 of the construction before described. The throttle casing 20 is supported from the smoke box shell and the steam pipes are of substantially the same construction and arrangement as in Figs. 1 and 2, the ends of the steam pipes being connected respectively to the throttle casing and the chest by joints 15 and 16, and the two sections of each steam 110

pipe being connected by a joint 19, such as described.

The arrangement of Figs. 3 and 4 also provides a measure of flexibility sufficient to take care of the greater expansion of the steam pipes without distorting the throttle casing or imposing material thrust on its support.

What I claim is:

- 10 1. In a locomotive, the combination of a smoke box, a dry pipe, a steam supply casting in the smoke box receiving steam from said dry pipe, a valve chest, a section of steam pipe having a jointed connection to said steam supply casting, a second section of steam pipe angularly disposed with respect to the first section and having a jointed
- 15

connection to said valve chest, and a jointed connection between the other ends of said sections.

2. In a locomotive, the combination of a smoke box, a dry pipe, a superheater header in the smoke box receiving steam from said dry pipe, a valve chest, a section of steam pipe having a jointed connection to said superheater header, a second section of steam pipe having a jointed connection to said valve chest, and a jointed connection between the other ends of said sections which is angularly disposed with respect to one of said other jointed connections.

In testimony whereof, I have hereunto signed my name.

WILLIAM L. REID.
